UNITED STATES PATENT OFFICE

RUBEN B. LUSTIG, OF KANSAS CITY, MISSOURI

DESIGN FOR A DISPLAY TABLE

Application filed November 3, 1930. Serial No. 37,501. Term of patent 14 years.

To all whom it may concern:

Be it known that I, RUBEN B. LUSTIG, a citizen of the United States, residing at Kansas City, in the county of Jackson and State of Missouri, have invented a new, original, and ornamental Design for Display Tables, of which the following is a specification, reference being had to the accompanying drawings, forming part thereof.

Fig. 1 is a perspective view of a display table, showing my new design. Fig. 2 is a plan view of the same.

I claim:

The ornamental design for a display table, as shown.

RUBEN B. LUSTIG.
